UNITED STATES PATENT OFFICE.

IVAR RENNERFELT, OF DJURSHOLM, SWEDEN.

ELECTRIC FURNACE.

1,305,167.

Specification of Letters Patent. Patented May 27, 1919.

Application filed October 3, 1918. Serial No. 256,651.

To all whom it may concern.:

Be it known that I, IVAR RENNERFELT, a subject of the King of Sweden, residing at Djursholm, in the Kingdom of Sweden, 5 have invented a new and useful Improvement in Electric Furnaces, of which the following is a specification.

This invention relates to improvements in electric furnaces.

10 Heretofore it has been known to heat objects in a furnace by means of centrally located vertical electrodes which generate arcs in contact with a furnace bottom adapted to rotate and provided with a contact bed of 15 carbon of a suitable kind.

Such furnaces are, however, impractical, since the electrodes are apt to break off if made to enter the rotating bed, especially if the bed is to be used as a heating 20 resistance.

Furthermore it is impossible in furnaces of this type to connect the electrodes alternately in delta and star connection, which clearly is desirable in order to facilitate the 25 control of the energy consumed by the furnace.

It has also been heretofore known to heat an object centrally located in a furnace room, for instance a crucible, by means of 30 two electric arcs, burning between two pairs of horizontal electrodes and heating opposite sides of the crucible. This way of heating offers, however, several disadvantages. Not only is it impossible to uniformly heat

35 a comparatively high object by means of horizontal arcs but it also is difficult to run a furnace of this kind with power from a supply circuit sensitive to fluctuations in the consumption of energy. This is the 40 case especially at the period of starting when the furnace is cold.

This type of furnace is, furthermore, not well adapted to be run by means of polyphase current in view of the fact that no 45 less than six electrodes are required which occupy considerable horizontal floor space. The arrangement of the electrodes also makes it difficult to equip the furnace with a sufficiently large charging door in the 50 sidewall thereof.

It is possible to avoid the disadvantages 55 enumerated above and to build a very useful and suitable furnace, if, as is contemplated by the present invention, a plurality of electrodes are arranged in the furnace

chamber near the sidewalls thereof so as to leave a free space in the center strongly heated and adapted to be used for melting or otherwise heating a charge in said space between the electrodes. 60

For certain purposes, especially when melting high grade glass for lamps, lenses, etc., one or more crucibles may preferably be placed directly on the bottom of said open space, facilitating a rapid melting and 65 removal when necessary.

A prominent feature of the present invention resides in the use of crushed carbon, coke, graphite or any other suitable material, which is preferably located on supports 70 which extend from the bottom and sides of the heating chamber of the furnace in such wise as to provide contacts for the arcs of the electrodes. These supports or extensions are built of highly refractory material for instance magnesite bricks or 75 bricks of carbon or graphite. The sidewall of the furnace immediately behind each arc should also be protected against the exceedingly strong heat by means of very refractory materials. 80

The contacts provided around the sidewall of the furnace may be connected either directly to each other using star connection or to the supply circuit. The arcs in this 85 way are connected in delta causing the voltage of the arcs to increase by 73%. Conductors of for instance carbon are used for leading the current through the sidewalls.

Both direct and alternating current may 90 be used. The frequency and number of phases is of no importance. The energy required is divided on a plurality of electrodes, their number depending on the number of phases and on the strength of current 95 allowable on each electrode of a certain dimension. The number of electrodes is also to be determined by the necessity of obtaining a suitable distribution of the heat. In furnaces of comparatively small size 100 employing single phase or direct current a distribution of the energy on two or more electrodes may, for reasons stated above, be required.

Clearly the distribution of a high and 105 uniform heat over a large surface in the center of the heated room is very much easier in a furnace constructed in accordance with the present invention than in furnaces of other types. The reason for this is 110

that the heat is radiated inward not only from the arcs themselves but also from the walls by reverberation.

The means for introducing energy into the furnace are furthermore very simple and easy to arrange in a furnace not employing centrally located heating devices in connection with a rotating bottom or a bottom contact.

10 In the accompanying drawings two embodiments of the invention are illustrated. Figures 1 and 2 are vertical and horizontal sectional views, respectively, of a furnace constructed for heating a plurality of crucibles, and Fig. 3 is a horizontal sectional view of a furnace constructed for heating only one crucible, said crucible being heated by means of a plurality of electrodes. Any kind of current may be used in operating either furnace.

The electrodes 1 may be vertical or introduced in an inclined position through the roof 2 or the sidewall 3 of the furnace. One or more crucibles 4 are placed in the center 15 of the furnace for melting glass or other substances. By arranging the bottom of the furnace as a melting hearth crucibles may be dispensed with.

Extensions 5 project from the sidewall, 20 carrying a suitable contact material 6 for instance of coke or graphite more or less finely crushed and preferably supported by a layer 7 of bricks or plates of carbon or graphite. In order to protect the wall 3 against the 25 intense heat given off by the heating arcs 8 it is preferred to place highly refractory plates 9 around said wall immediately behind the electrodes. At this place openings 10 may be arranged for observing the arcs 10 and for introducing the contact material 6. Other openings 11 in the sidewall permit 30 charging of the crucibles and may be used also for removing glass with for instance a blowpipe. To remove the crucibles openings 45 12 are provided in the sidewall.

The invention may be applied also to furnaces which are oval or rectangular in cross section and which are provided with any number of crucibles. The crucibles, how-

ever, should not be made too deep in view of 50 the fact that the melting of the charge would thereby be rendered difficult. The electrodes may be movable up and down and may be given various angular adjustments, as desired. The roof of the furnace may, 55 for several purposes, be made removable.

In the use of furnaces constructed in accordance with the present invention, the carbon particles which fall from the electrodes during a heating operation do not enter the 60 materials being melted, as is the case in furnaces of the type wherein the electrodes are located centrally above the charge instead of being arranged adjacent the sidewall of the furnace and to one side of the 65 materials being treated as in the furnaces illustrated in the accompanying drawings. If desired channels may be provided in the bottom of the furnace for special heating purposes, resistances being located in said 70 channels. If desired electrodes may be used instead of resistance material for this purpose.

I claim:

1. In an electric furnace the combination 75 of a plurality of electrodes projecting downward into a heating room toward projections from the side wall corresponding to each electrode and supporting carbonaceous contact material for arcs from the electrodes. 80

2. In an electric furnace the combination of a plurality of electrodes projecting downward into a heating room toward projections from the side wall corresponding to each electrode and supporting carbonaceous contact 85 material for arcs from the electrodes and means for changing the connection of the electrodes with the source of power from delta to star coupling.

3. In an electric furnace the combination 90 of a plurality of electrodes projecting downward into a heating room toward projections from the side wall corresponding to each electrode and supporting carbonaceous contact material for arcs from the electrodes 95 and a crucible located in the heated space between the arcs.

IVAR RENNERFELT.
